E. D. DUNNING

COMPRESSION PUMP

Original Filed April 29, 1919

FIG., 1

FIG. 2

4 INVENTOR
Elmer W. Reinising
BY
George H. Davis ATTORNEY

UNITED STATES PATENT OFFICE.

ELMER D. DUNNING, OF PHILADELPHIA, PENNSYLVANIA.

COMPRESSION PUMP.

Application filed April 29, 1919, Serial No. 293,387. Renewed September 27, 1923.

To all whom it may concern:

Be it known that I, ELMER D. DUNNING, a citizen of the United States, and resident of Philadelphia, in the county of Philadelphia and State of Pennsylvania, have invented certain new and useful Improvements in Compression Pumps, of which the following is a specification.

My present invention relates to compression pumps of the type commonly employed as tire pumps and particularly to the smaller and more compact types adapted to be installed on the frame of an automobile engine. Such pumps are required to deliver compressed air at pressures up to say 60 pounds for the smaller tires and to operate with decreasing volume of output and decreasing efficiency at the higher pressures required for larger tires up to say 90 to 120 pounds.

For such purposes it is common to employ a double pump comprising two piston heads rigidly connected base to base and reciprocated in oppositely aligned cylinders by a special form of scotch yoke driver consisting of an eccentric fitted between the adjacent bases of the piston heads and acting alternately on one and then on the other to force the compression strokes of each, the suction strokes being accomplished by traction through the rigid connection between the heads.

My present invention consists in certain important improvements in pumps of this type.

For instance, such pumps for such purposes so far as I am aware have the ratio of piston area to stroke, usually about 3 to 1, that is to say, 3 square inches of piston area for one inch stroke, or $2\frac{1}{2}$ square inches for a $\frac{1}{4}$ inch stroke. This gives a transverse strain on the drive shaft of say 300 pounds when pumping against 100 pounds back pressure which is quite as high as is safe for such devices as ordinarily constructed. Nevertheless, I have discovered that for the particular numerical values here involved, many advantages can be gained by doubling the piston area without increasing the stroke, for instance, if the stroke be kept $\frac{1}{2}$ inch and the piston diameter increased to $2\frac{3}{8}$ inches the area will be about $4\frac{1}{2}$ inches which gives a ratio of piston area to stroke of about 6 to 1 instead of 2 or 3 to 1. I thereby double the volume of the pump space while the circumference

where leaks can occur is increased only 20%. This averages out a 40% decrease in possible leakage besides practically doubling the capacity of the pump.

It is true the doubling of the piston area will bring the transverse strain on the drive shaft up to 450 pounds when pumping at 100 pounds per square inch, but this is taken care of by an improved bearing and proportioning for the drive shaft while the increased diameter of the pump heads gives added space for a much wider and more centrally located driver, without encroaching on the space necessary for structural strength of the rigid member connecting the two piston heads.

While certain variations are possible in these dimensions without departing from the spirit of this part of my invention, I prefer that the ratio of piston area to stroke be not less than 5 to 1 nor more than 8 to 1 and that the stroke be not less than $\frac{1}{2}$ of an inch nor more than 1 inch with the clearance at the end of the stroke not more than one-sixth the stroke nor less than $\frac{1}{2}$ inch.

The rotary crank element is preferably formed as an eccentric circle of relatively large diameter, said diameter being approximately twice the stroke or four times the radial distance between the center of the eccentric head and the axis of the drive shaft. This radius will be $\frac{1}{2}$ inch for a $\frac{1}{4}$ inch stroke and as the load acts at right angles to this radius only at mid-stroke, when the back pressure in the compression space is not over about 15 pounds per square inch, its torque load on the crank shaft even for $4\frac{1}{2}$ inch piston area, is not over 100 pounds plus frictional resistance which is small because of the peculiar design employed.

Many other features of my invention relate to structural improvements and most of them may be embodied in pumps of different proportions, and some of them in pumps which have only a single piston head and pump chamber. These improvements include the following:

In the double headed piston the two heads are connected by a solid longitudinal member unweakened by slotting for the drive shaft and guided and prevented from rotation by contact with the end face of the rotary crank element. The friction surface of this sliding contact may be reduced by hollowing out the end thrust surface of the rotor so as to leave an annulus of desired

width, and the hollow may be extended deep enough to materially decrease the eccentric weight, provided the walls are kept thick enough to have the necessary strength. The 5 diameter of the drive shaft is almost equal to the crank throw. It is mounted in a single, overhung bearing. The bearing extends substantially to the plane of the rotor and is formed with end thrust surfaces for 10 maintaining the rotor accurately in position.

The double pump chamber consists of a single straight bored cylinder. The respective inlet and outlet passages and valve seats therefor are drilled straight across in the 15 heads which close the cylinder at either end and the outlet passages communicate with a straight outlet passage drilled in the wall of the cylinder from end to end therof.

The length of the shaft bearing is more 20 than four times crank radius and is removably but rigidly secured by a cylindrical exterior bearing surface accurately machined to fit an opening formed therefor in the side of the cylinder casing and by an 25 annular face fitting against the mouth thereof at right angles to the cylindrical bearing surface. The opening in which the cylindrical bearing fits is preferably of slightly greater diameter than the eccentric 30 driving head so that the bearing, drive shaft and head may be radially inserted in or removed from the cylinder by simply removing the screws which hold the annular flange in place.

35 Means for throwing the drive shaft into and out of driving engagement with a suitable source of power as for instance the cam shaft of an automobile engine, is provided in the form of a clutch collar splined to the 40 drive shaft and movable endwise thereon by a swivel fork pinned to an endwise movable shaft slidably supported parallel with the drive shaft and adapted to be non-positively locked in the operative or inoperative 45 position of the clutch by a spring pressed ball arranged to laterally engage suitably spaced notches in said movable shaft.

The above and other features of my invention may be more fully understood from the 50 following description of a desirable embodiment thereof in connection with the accompanying drawings, in which—

55 Figure 1 is a horizontal section on the axis of the device, and

Figure 2 is a vertical section at right angles to the axis.

As shown in these drawings, the body of the pump comprises a cylindrical casting 1 having a straight cylindrical bore and 60 formed exteriorly with radiating flanges 3, suitable standards or supports 4, formed with bolt holes 5 for securing the same, a longitudinal rib 6 having a straight outlet passage 7 drilled therethrough and a transverse outlet passage 8; also a lateral opening

9 having straight walls 10, and a flat face 11. The opening is of size sufficient to permit crank shaft and rotor to be inserted or withdrawn, the said opening being normally closed by the crank shaft bearing when the 70 latter is in position.

Fitting the cylinder bore 2 is a double faced piston comprising oppositely facing piston heads 13, which may be provided with elastic steel rings 14 of the type commonly employed for pistons of automobile motors. Said piston heads are rigidly connected and preferably cast integral with a longitudinal member 15 having a strengthening rib 16 and a flat face 17 extending parallel with the axis of the cylinder. At right angles to the ends of said face, are parallel bearing surfaces 18, said surfaces 18 and 17 being of shape and dimensions adapted to fit the rotary driving member on two sides and the 85 end thereof, respectively.

The cylinder is closed by similar heads 20 each comprising a circular casting having air inlet and outlet passages drilled therein, preferably all in the same straight line. These passages are preferably formed by drilling a through hole of the size of the central part of the passage 22, reaming enlargements 23 from each end to form shoulders 24, then screw-threading for screw-plug 25 and sleeve 26. The inner end of the screw sleeve 26 is formed with a valve seat 27 for inlet valve 28 normally held in the closed position by spring 29 resting on shoulder 24. The other shoulder 24 forms a valve seat for outlet valve 31 normally held closed by spring 32 abutting against screw-plug 33. The passage 22 has a central opening 34 communicating with the pump chamber, preferably at the center thereof.

The outlet passages have lateral openings 35 registering with the outlet passage 7 formed in the wall of the cylinder. The cylinder heads are held in place by suitable screws or bolts not shown.

The removable bearing member 40 fits into and closes the opening 10 and has a projecting portion 42 supporting the drive shaft 43 up to a point closely adjacent the rotor 44, and of reduced diameter toward the end so as not to interfere with rearward movements of the piston heads. It also has a rear extension 45 which makes the total length of the bearing very great as compared with the crank radius. It also has an extended bearing 46 contacting firmly with the interior of walls 10 and an annular flange 47 adapted to be secured by screws 48.

As a means for connecting the drive shaft and source of power, I provide a clutch collar 50 having longitudinal projecting lugs 51 slidably secured on the drive shaft by a semi-circular spline 52 engaging slot 53. The clutch collar has a swivel groove 54

around which fits fork 55 secured to shaft 56 by taper pin 57. The shaft 56 is slidably supported in a lug 58 on the cylinder, preferably integral therewith and in a lug 59 5 preferably integral with the drive shaft bearing, adapted to support shaft 56 close up to the plane of the clutch collar.

The shaft 56 may be supplied with operating handle 60 for shifting it endwise and 10 may be non-positively secured in the operative or inoperative position by pressure of spring 61 on ball 62 located in drill hole 63 and engaging notches 64 on the under side of shaft 56.

15 Structurally the device is extremely simple and composed of extremely few parts very unlikely to get out of order and very easy to replace or repair, the essentials exclusive of fittings, consisting of a single 20 piece cylinder, a single piece piston, a single piece drive shaft and eccentric and single piece bearing, and two single piece cylinder heads. The fittings also are simple and few in number comprising only the four 25 valve plugs, balls and springs, the four piston rings and 16 screws, 6 for each head and 4 for the bearing. The clutch device is equally simple comprising only spline, 30 collar, fork, shaft, pin, ball and spring.

35 The pump is well adapted for operation at 6 to 8 hundred revolutions per minute and can be driven up to a thousand or fifteen hundred revolutions for short periods. Hence, it is peculiarly adapted for driving from any exposed rotating shaft or other

part of the motor or transmission by either positive or frictional connection which may be either a clutch or a gear.

I claim:

1. In a double pump, a single straight 40 bore tube forming opposed cylinders, a one piece web connected, double faced piston, a single piece combined eccentric and drive shaft, a suitable bearing support for the shaft, and one piece detachable cylinder 45 heads with inlet and outlet valves located therein.

2. In a pump, a one piece cylinder, an outlet passage through the cylinder wall and extending in the direction of the length of 50 the cylinder, a one piece detachable cylinder head closing one end of the cylinder, an opening or passage extending through said cylinder head, and connecting the cylinder 55 with the outlet passage.

3. In a pump, a one piece cylinder, an opening or passage through the cylinder wall and extending in the direction of the length of the cylinder, one piece detachable 60 cylinder heads closing the ends of the cylinder, an opening or passage extending through said cylinder heads and opening into the outlet passage and the cylinder, and valves placed in the cylinder head passage 65 to form inlet and outlet valves for the cylinder.

Signed at New York city, in the county of New York and State of New York, this 24th day of April, A. D. 1919.

ELMER D. DUNNING.
